UNITED STATES PATENT OFFICE

ISIDOR TORNBERG, OF PLAINFIELD, NEW JERSEY, ASSIGNOR TO WOOD NEWSPAPER MACHINERY CORPORATION, OF NEW YORK, N. Y., A CORPORATION OF VIRGINIA

INK-FOUNTAIN DRIVE

Application filed September 23, 1927, Serial No. 221,453. Renewed May 9, 1930.

This invention relates to driving means for the ink fountain of a printing press, particularly of a press involving a number of units.

5 The principal objects of the invention are to provide means whereby the different fountains can be driven from the regular source of power used for driving the remainder of the press, at a speed proportionate to the latter through various ranges and stages of speed as may be desired; to provide for application of the power to the fountains to drive them independently of the remainder of the press for the purpose of properly cutting 10 up and distributing the ink uniformly on the cylinders before any paper is fed through the machine; to provide for driving all the fountains in any given number of units, either independently or collectively from a 15 single point without running the remainder of the press; to provide in the same machine for driving the fountains at a rate of speed disproportionate to that of the press; to provide for maintaining constant alignment between the motor and the fountain and to provide a construction in a simple form involving few parts and those of such a nature as to be easily assembled and taken care of.

20 Other objects and advantages of the invention will appear hereinafter.

Reference is to be had to the accompanying drawings in which

25 Fig. 1 is a diagram of a newspaper printing plant arranged according to this invention;

Fig. 2 is a side view of a newspaper printing press showing a preferred arrangement;

30 Fig. 3 is a plan showing one form in which each motor for driving an inking fountain can be arranged, and

Fig. 4 is a sectional view of the same on the line 4—4 of Fig. 1.

35 Heretofore in driving newspaper printing machines involving a plurality of printing units, the several ink fountains have been geared directly to the press. This limited the number of speed variations, if any were provided at all, between the fountain and the driving mechanism of the press unit. Obviously it is difficult to introduce any gear

changes between the fountains and the press. Furthermore, this makes it necessary to run the whole press if the fountains are to be run and does not allow of the varying of the speed of the ink fountain finely enough to 55 suit inking requirements. It has been necessary heretofore to ink up each fountain independently before starting on a run, thus wasting much time. The inking mechanisms also could not be run at a disproportionate 60 speed, if desired, for certain purposes.

This invention is shown as applied to a well known type of printing press, usually employed for newspaper work in which of course each couple is provided with an ink 65 fountain 10. Each ink fountain cylinder is driven by an individual electric motor 13, which, in the form shown, is located directly on the fountain and drives the cylinder through a worm 14 and worm wheel 15, the 70 latter being mounted on the shaft 16 of the fountain cylinder.

75 Each of the motors 13 is controlled by a rheostat 18 which is located in the control circuit for the press. It will be seen that the current can be sent through any individual motor to drive that motor at any desired speed without driving the others. Furthermore each rheostat 18 can be set at the proper point to drive its motor correctly and then 80 the motors will all be connected up with a direct current line. A relay 19 is used to short circuit the rheostat. The relay is connected to be operated from the circuit coming from the controller with which the printing press is provided. Thus, it is possible, at a very low speed of the press, to cut out the rheostat or any part of it that may be desired for the purpose of varying the speed 85 of the fountain cylinder driving motors at 90 different points of the controller setting, in addition to the ability to vary the speed manually.

95 The armatures of the motors are fed from an electric current generated by a direct connected generator 20 driven by the main driving motor 21 of the press, the speed of which varies with the speed of the press. This keeps the speed of the fountain driving motors proportionate to the speed of the press within 100

any range desired by adjustment of the above mentioned rheostats. The field of the generator and the fields of the fountain driving motors are fed from a single direct current supply that is controlled through one or more fixed or adjustable rheostats 22 adapted to be short-circuited by a relay 23 which in turn is controlled by the press controller (not shown).

10 The main rheostat (not shown) is connected up with the main motor to drive that for operating the press couples at any desired speed, the rheostats 18 all being set correctly. The several ink fountain cylinders will be driven in accordance with the setting of the main rheostat, that is, they will be driven at a speed proportional to the speed of the press at all times when running through the main rheostat. In spite of this fact the several 15 rheostats 18 can be turned to change the speed of their motors 13, or any of them can be cut out and yet the others can be run without running the press.

With this arrangement a distinct advantage can be secured because of the ability to 20 drive the fountain cylinders controlled by the ordinary controlling device for the press controlled from the main rheostat. In this case the fountain cylinders are driven at a speed 25 proportionate to the speed of the motor for running the press. If that changes, the speed of the fountain cylinders will change with it because both are under the control of the main rheostat.

30 A switch 24 is provided for connecting the armatures of one or more of the fountain driving motors directly to the direct current supply instead of to the generated current. This serves the purpose of rotating them independently of the press, or while the press 35 is at a standstill. It also serves as an emergency source of current supply in case the generator fails to function for any reason. An individual snap switch 25 may be used 40 to disconnect any of the motors from the circuit.

The fountains can be run independently, as stated, while the press is not running to 45 properly prepare the ink of the ink drums before any paper is fed through. The fountains in any given number of units may be controlled independently or collectively from a single point.

50 Although I have illustrated and described only one form of the invention I am aware of the fact that modifications can be made therein by any person skilled in the art without departing from the scope of the invention as expressed in the claims.

55 Therefore, I do not wish to be limited in these respects but what I do claim is:

1. In a printing press, the combination with a main motor for driving the press, and a plurality of ink fountain cylinder motors, 60 of a generator driven by the main motor,

and means for conducting the current from the generator to the ink fountain cylinder motor armatures to drive them.

2. In a printing press, the combination with a main motor for driving the press, and 70 a plurality of ink fountain cylinder motors, of a generator driven by the main motor, means for conducting the current from the generator to the ink fountain cylinder motor armatures to drive them, a source of direct 75 current connected with the fields of the ink fountain cylinder motors, and individual regulating devices for said fields.

3. In a printing press, the combination with a main motor for driving the press, and 80 a plurality of ink fountain cylinder motors, of a generator driven by the main motor, means for conducting the current from the generator to the ink fountain cylinder motor armatures to drive them, a source of direct 85 current connected with the fields of the ink fountain cylinder motors, and means for supplying the field of the generator from said source.

4. In a printing press, the combination with 90 a main motor for driving the press, of a generator connected with the motor to be driven thereby, a series of ink fountain cylinder operating motors having their armatures connected with the generator to be 95 driven by the current therefrom, a source of direct current connected with the fields of said fountain cylinder motors, and means by which the armatures of the fountain cylinder motors can be connected with said 100 source of direct current when desired.

5. In a printing press, the combination with a main motor for driving the press, of a generator connected with the motor to be driven thereby, a series of ink fountain cylinder operating motors all connected with the generator to be driven by the current thereof, a source of direct current connected with the fields of said fountain cylinder motors and with the field of said generator, 105 a switch in the line from the generator by which the armatures of the fountain cylinder motors can be connected with said source of direct current when desired, and a rheostat connected with said source of current to 110 control the field of the generator.

6. In a printing press inking mechanism, the combination with a fountain, and a motor mounted on the fountain, of means for connecting said motor directly with the inking 115 mechanism to drive the same, a main motor for driving the press, a generator driven by the main motor and means for driving the ink fountain motor through said connecting means and by the current produced by the 120 generator.

7. In a printing press inking mechanism, the combination with a fountain, a motor fixed on the fountain, the shaft of the motor having a worm thereon, a worm wheel mesh- 125

ing with and driven by the worm, and a fountain roll constituting a part of the inking mechanism connected with said worm wheel to operate therewith.

5 In testimony whereof I have hereunto affixed my signature.

ISIDOR TORNBERG.
